UNITED STATES PATENT OFFICE

2,192,449

APPARATUS FOR WAVING HAIR

Renato Ludovici, Chicago, Ill.

Application October 1, 1937, Serial No. 166,710

12 Claims. (Cl. 132—33)

This invention relates to the waving of hair upon the human head, and particularly, to improvements in apparatus for the production of so-called "permanent" waves in Croquignole fashion.

Heretofore, in the practice of Croquignole waving, it has been customary to divide the hair into flat strands and to secure each strand of hair adjacent the scalp by means of a clamp adapted to firmly grip the hair, and thereafter to wind the hair from the ends on a curler rod, subjecting the strand to tension from the point where it is gripped by the clamp. The clamp is usually provided with a locking or clutch device for holding the curling rod in a tightened position, whereby the tension is maintained after the hair is wound and while it is moistened with a suitable solution, wrapped and subjected to heat to bake the curl therein.

In order to avoid pulling the hair at the roots and causing discomfort to the subject, it has been necessary to employ a clamp which will grip the hair firmly and tightly.

It is a well known fact that in order to impart so-called "permanency" to the waved hair, it is necessary that the hair must be wound tightly on the curler with all portions of the strand placed under tension, for, if any portion of the strand of hair should not be under tension, it will not be effectively and permanently waved. It is important, therefore, that the tension applied to the strand of hair should be uniform throughout the entire strand, and this uniformity of tension should also be applied to adjacent strands in order to produce uniform and satisfactory waves.

In the Croquignole method heretofore used, the devices available therefor have been unsatisfactory, primarily because of the impossibility of the application of substantially uniform tension to the hair as the same is being wound. The operator had no means for gauging the tension to which the hair is subjected, with the result that the strand of hair is either over-wound, thereby causing a weakening of the hair, or under-wound, resulting in a wave which would not withstand shampooing and would, therefore, lose its wavy effect after a short time.

It is the main object of the present invention to provide a simple and effective apparatus for waving hair, in which the disadvantages of previous practices are avoided. By employing my present invention, it is possible to have all portions of the strand of hair wound under substantially uniform tension upon the curling pin,

55 which tension does not depend merely upon the

guesswork or skill of the operator, and which is applied as the hair is wound at a substantially uniform rate, instead of after the winding is completed, by giving to the curling pin a final turn as in the practice heretofore followed.

Another object of the invention is the provision of a simple device, permitting the application of uniform tension automatically as the hair is being wound, the tension being governed by means associated with these devices, so that the same is applied substantially automatically and is, therefore, independent of the operator's judgment.

A further object of the invention is the provision of simple and effective apparatus to facilitate the winding of a strand of hair in Croquignole fashion under substantially uniform tension, without exerting any pull whatsoever on the hair at the roots, thereby eliminating any discomfort to the subject and preventing injury to the scalp.

A still further object of this invention is to provide novel and improved devices for carrying out my improved procedure, which devices may be simple in construction, assembly and operation, which may be constructed along lines convenient for low cost manufacture, and which will, at the same time, be highly efficient for carrying out the purposes for which they are designed.

With the foregoing and other objects in view, which will appear as the description proceeds, the invention consists in certain novel features of construction, arrangement and combination of parts hereinafter more fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawing preferred embodiments thereof, from an inspection of which, when considered in connection with the following description, my invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is an elevation, showing the first step

in winding the hair upon the winding or curling pin;

Fig. 2 shows the application of the tension device to the hair, and the attachment of the winding pin to the tension device preparatory to the completion of the winding of the hair upon the winding pin, two positions of the tension device being illustrated;

Fig. 3 is an elevation, showing the completion 10 of the wind, with the tension device disposed adjacent to the scalp;

Fig. 4 is a sectional view, illustrating the final position of the winding means with respect to the scalp;

Fig. 5 is a view in perspective of the shields applied to the flat strand of hair before the winding operation is begun;

Fig. 6 is a view in perspective, illustrating the preferred form of apparatus for practicing the 20 invention.

In carrying out my invention, the hair on the scalp is first divided into a plurality of strands 10, each of which is separately treated in the manner to be hereinafter described. The strand 25 10, after the same has been blocked off on the scalp, is drawn through a slit 11 formed in a shield 12, which shield may be constructed from a layer of flannel or felt 13, to the outer face of which may be secured a layer 14 of rubber, asbestos or other suitable material, the object of which is to prevent transmission of heat to the scalp.

In order to further protect the scalp, there may also be provided a shield 15 constructed from a sheet of insulating material 16, to the inner face of which may be stitched a layer of felt 17 by means of the stitching 18, such shield having a slot 19 arranged longitudinally thereof, said slot being open at one end, as shown in Fig. 40 5, through which open end the strand of hair 10 may be received.

The winding pin or roller 20 on which the lock of hair is adapted to be wound, is similar to winding pins heretofore used in producing the 45 Croquignole wave and comprises two substantially cylindrical ends 21 and 22, and with the body of the pin between these ends gradually tapering towards the middle portion which is the smallest diameter of the pin, so that the thicker 50 portion of the lock of hair is accommodated on the reduced diameter of the pin, whereas the sides of the lock of hair are wound on the portions of increased diameter.

The rod 20 is provided with a clip 23 pivotally 55 secured thereto at 24, which clip is adapted to be placed against the free end of the lock of hair, as shown in Fig. 1, to hold it until a few turns are rolled from the ends of the hair, after which the hair will be firmly secured to the rod. The 60 curling rod 20 is provided with a knurled head 25 and a circumferential groove between said knurled head 25 and cylindrical portion 21 at one end of the rod, and a recess 27 in the other end of the rod. Mounted within said recess 27 is a stud 28, said stud being secured for rotary movement within said recess by means of the pins 29, and is provided with the means 30 for cooperating 65 with the serrated surface 31 of the inner wall of the recess for permitting rotation of the rod 20 in one direction, but preventing rotation thereof in the opposite direction. That portion of the stud 28 extending beyond the recess 27 is provided with a squared portion 32 for a purpose to be presently more fully described.

After the strand of hair has been partially

wound on the rod 20, the next step, as indicated in Fig. 2 (in solid lines) is to engage the rod 20 within my improved tension device, as shown in Fig. 2 (in dotted lines). My improved tension device includes a pair of frame members 33 and 34 pivotally secured to each other at 35, whereby said frame members are adapted for swinging movement towards each other. The frame member 33 comprises a pair of side arms 36 and 37, to the outer ends of which is secured a connecting rod 38, upon which rod may be fixedly secured a sleeve or casing 39, preferably of rubber, although any suitable material adapted to afford a degree of friction may be employed. This casing 39 is arranged on the rod 38 so as to be non-rotatable thereon. The upper surfaces or edges of the arms 36 and 37 are curved to produce the cam surfaces 40, for a purpose to be presently more fully described. The frame 10 34 comprises a pair of side arms 41 and 42, to the outer ends of which is rigidly secured a connecting rod 43, upon which is fixedly secured a sleeve or casing 44, preferably of rubber, although any suitable material adapted to afford a degree of friction may be employed. The arms 36 and 20 41 are provided with cut-out portions 45 and 46, which portions will form a substantially square opening when the tensioning device is moved to closed position, as shown in dotted lines of Fig. 2 of the drawing. Similarly, the arms 37 and 30 42 are provided with the cut-out portions 47 and 48, which will form a substantially circular opening when the tensioning device is moved to the closed position, as shown in Fig. 2 in dotted lines. In these openings is adapted to be disposed respectively, the squared end 32 of the curling rod 20 and the reduced portion 26 of the opposite end of said curling rod.

Secured to the arm 41 is a stud 49, to which is pivotally secured one end of a wire spring 50, the other end of said spring being provided with a hook portion 51, which is adapted to engage over the cam surface 40 provided on the arm 36, to exert tension thereon for bringing about the desired contacting engagement between the members 39 and 44 for pressing the strand of hair 13 therebetween. Similarly, the arm 42 has a stud 52 secured thereto, to which is pivotally secured one end of a wire spring 53, the other end of which spring is provided with a hook portion 54 adapted to engage the cam surface 40 of the arm 37. The spring members 50 and 53 are of sufficient strength and resiliency to give the desired gripping action to the members 39 and 44, the friction surfaces of the members 39 and 44 bearing against each other when the tensioning device is in the position shown in Fig. 2 in dotted lines.

The curling rod 20 is provided adjacent the knurled portion 25 with a squared extension 55, 60 which is adapted for engagement within a recess 57 of a hand tool 56, the latter being effective for facilitating the rotating of the curling rod when the hair is being wound thereon.

The operation of my improved apparatus in 65 practicing the procedure disclosed herein may be described as follows: The hair on the scalp is first divided into a plurality of strands, and the first step in treating each of said strands is to apply thereto the shield 12 by drawing the strand 70 through the slit 11 and then moving the shield along the strand until it rests against the head of the subject. If desired to insure still further protection against the further transmission of heat to the scalp, a shield 15 may also be ap- 75

plied, which shield it will be noted, will be disposed against the first shield 12 as shown more clearly in the drawing. The next step is to apply the curling rod 20 to the free ends of the strand of hair, which is done by twisting the end of the strand of hair one or more times around the middle portion of the curling rod while the clip 23 is swung out, and then this clip is swung back to hold the hair which has been applied to the curling rod. The curling rod may be given several turns now without exerting much pull on the strand, so as to insure that the hair is firmly secured to and well started on the curling rod, and as no pull is exerted during this initial winding, it will be apparent that the same will cause no discomfort to the subject.

The next step is to apply the tensioning device comprising the frames 33 and 34 to the curling rod with the strand of hair partially wound thereon. This is done by arranging the reduced portion 26 of one end of the curling rod in the cut-out portion 43 of the side arm 42 and the squared portion 32 of the opposite end of the curling rod in the cut-out 46 of the side arm 41. The frame members 33 and 34 are now swung towards each other so as to securely lock the ends of the curling rod in the openings formed by the cut-outs 45-43 and 47-46, in which position these frame members may be held by the operator until the spring members 50 and 53 are swung about their pivots in a clockwise direction, so that their respective hook portions 51 and 54 will engage over the cam surfaces 48 of the side arms 36 and 37 to securely lock the tensioning device in fully operative position, which position is indicated in dotted lines in Fig. 2.

The said spring members 50 and 53, as already stated, are constructed so that when moved to their fully operative position, they will cause the members 39 and 44 to be tightly pressed against each other and against the strand of hair disposed therebetween. The curling rod 20 is then rotated to wind the hair thereon, and tension is automatically applied to the hair from the free ends as it passes between the friction surfaces 39 and 44. The resistance to the movement of the hair by these surfaces causes the hair, which is wound upon the curling rod, to be drawn taut and to be placed under tension. Meanwhile no tension is maintained between the scalp and the point where the strand of hair is gripped between the members 39 and 44. As the curling pin is rotated, the tensioning device, with the winding pin secured therein, moves towards the scalp until it reaches the position indicated in Fig. 3, where it rests upon or against the shields 12 and 15.

The curling rod is prevented from rotating in the reverse direction by engagement of the pawls 38 with the ratchet teeth 31 provided in the recess 27 at one end of the curling rod. In the final position of the tensioning device resting on the protectors 12 and 15, the strand of hair is wound tightly on the curling rod 20 and is under tension from the free ends, the tension being regulated by the pressure of the friction surfaces 39 and 44 against the hair, but no tension is applied to the strand of hair in the direction of the scalp, and the hair is not subjected, therefore, to any pull at the scalp either during the winding or when the winding has been completed.

I have found from actual experiment, that the tensioning device will not operate efficiently unless the friction members 39 and 44 are mounted

so as not to be rotatable during the winding operation. In other words, the drag or holding action on the hair by said friction surfaces 39 and 44 must be due to the friction between the two surfaces, and said friction must be of a high degree, which is not possible when said members 39 and 44 are capable of rotary movement relative to each other. The resistance of the friction surfaces 39 and 44 to the passage of the hair therebetween while the same is being wound on the curling rod, will determine the degree of tension thereby given to the wound strand of hair. Thus, this degree of tension will depend a great deal upon the spring members 50 and 53. However, when once adjusted, the tension provided will be automatically applied to the hair and will be substantially uniform for all portions of the strand as well as for adjacent strands wound with the same tensioning devices.

With the completion of the winding of the several strands of hair on the scalp, said wound strands can be moistened with a suitable hair treating solution, wrapped in the usual pads and then heat applied to the wound strands by means of the usual heating devices commonly employed in Croquignole waving. These ordinarily consist of arcuate members containing electric heating elements with suitable insulating handles, and resilient means to hold the arcuate members in contact with the wrapped strands of hair. As the heating devices are well known in the art and form no part of the present invention, the same are not illustrated in the accompanying drawing.

It will be understood that in accordance with the usual practice, when the heating is completed, the heaters and wrappers are removed and the strands of hair are separated from the curling rods, after which the hair may be washed and otherwise treated to complete the wave.

It will be noted, however, that with my improved tensioning device, the same may be readily detached from the curling rod by swinging the spring members 50 and 53 in a counterclockwise direction, whereby the said device may be readily opened up and removed from the curling rod and the wound strand of hair.

It will be apparent from what has been described, that my improved procedure and apparatus permits the application of uniform tension to the entire strand of hair while, at the same time, avoiding any pulling of the hair at the scalp either during the winding operation or while the hair is being baked. It will also be noted that my improved apparatus is much simpler in construction and operation, and may be more easily applied than devices of this character heretofore employed.

It is believed that my invention, its mode of construction and assembly, and many of its advantages should be readily understood from the foregoing without further description, and it should also be manifest that while preferred embodiments of the invention have been shown and described for illustrative purposes, the structural details are nevertheless capable of wide variation within the purview of my invention as defined in the appended claims.

What I claim and desire to secure by Letters Patent of the United States is:

1. A hair waving device, including a winding element on which a strand of hair is adapted to be wound and a compression device adapted to be applied to the hair between said winding element and the scalp and including a frame adapted

- to receive and revolvably hold said winding element, and having means thereon for compressing the strand of hair throughout its entire width whereby tension will be placed on the hair as it is drawn by said winding element through said compression device, said compression device including cooperating non-rotatable friction members between which the strand of hair is drawn by said winding pin.
10. 2. A hair waving device, including a winding element on which a strand of hair is adapted to be wound and a compression device adapted to be applied to the hair between said winding element and the scalp and including a frame adapted to receive and revolvably hold said winding element, and having means thereon for compressing the strand of hair throughout its entire width whereby tension will be placed on the hair as it is drawn by said winding element through said compression device, said compression device including cooperating non-rotatable friction members between which the strand of hair is drawn by said winding pin, said friction members being arranged for pivotal movement relative to each other for permitting the strand of hair to be placed therebetween.
3. A hair waving device, including a winding element on which a strand of hair is adapted to be wound and a compression device adapted to be applied to the hair between said winding element and the scalp and including a frame adapted to receive and revolvably hold said winding element, and having means thereon for compressing the strand of hair throughout its entire width whereby tension will be placed on the hair as it is drawn by said winding element through said compression device, said compression device including cooperating non-rotatable friction members between which the strand of hair is drawn by said winding pin, and means for locking said members in operative position, in which position they will be incapable of movement relative to each other.
4. A hair waving device including a winding element on which a strand of hair is adapted to be wound and a compression device adapted to be applied to the hair between said winding element and the scalp and including a frame adapted to receive and revolvably hold said winding element, and having means thereon for compressing the strand of hair throughout its entire width whereby tension will be placed on the hair as it is drawn by said winding element through said compression device, said compression device including cooperating non-rotatable friction members between which the strand of hair is drawn by said winding pin, and resilient means for locking said members in operative position.
5. In an apparatus for waving hair on the human head, a compression device including a frame, a winding element adapted to be mounted therein, means associated with said winding element permitting rotation of the same in the frame only in one direction, and means on the frame adapted to continuously compress the strand of hair as it is drawn therethrough by said winding element, said compression device including a pair of cooperating non-rotatable friction members held against movement relative to each other.
6. In an apparatus for waving hair on the human head, a frame, a winding element adapted to be mounted therein, means permitting rotation of the winding element in the frame only in one direction, and means carried by the frame hav-

ing a pair of non-rotatable friction surfaces adapted to compress a strand of hair therebetween as it is drawn therethrough by said winding element.

7. In an apparatus for waving hair on the human head, a frame, a winding element adapted to be mounted therein, means permitting rotation of the winding element in the frame only in one direction, and means carried by the frame having a pair of non-rotatable friction surfaces adapted to compress a strand of hair therebetween as it is drawn therethrough by said winding element, said members with the friction surfaces being incapable of movement relative to each other.

8. In an apparatus for waving hair on the human head, a frame comprising a pair of pivotally mounted members provided with friction surfaces, resilient means for locking said friction surfaces into contacting engagement with each other, a winding element adapted to be mounted within said frame and having means permitting rotation of said winding element in the frame only in one direction, said friction surfaces being adapted to resiliently compress a strand of hair throughout its entire width as it is wound on the winding element, the degree of friction between said friction surfaces being such as to permit the hair to be tightly wound on said winding element while, at the same time, leaving the portion of the hair between the scalp and the point at which compression takes place by the friction surfaces unrestrained.

9. A hair waving device, including a winding element on which a strand of hair is adapted to be wound, and a compression device adapted to be applied to the hair between said winding element and the scalp, including a frame adapted to receive and revolvably hold said winding element, and having means thereon for compressing the strand of hair throughout its entire width as it is drawn by the winding element, said compressing means including cooperating non-rotatable members provided with friction surfaces between which said strand of hair is drawn by the winding element, resilient members mounted on said frame and adapted when in one position to permit the separation of said members, and when in another position to press said members towards each other and to resiliently hold the same in contacting engagement with each other.

10. A hair waving device, including a winding element on which a strand of hair is adapted to be wound, and a compression device adapted to be applied to the hair between said winding element and the scalp, including a frame adapted to receive and revolvably hold said winding element, and having means thereon for compressing the strand of hair throughout its entire width as it is drawn by the winding element, said compressing means including cooperating non-rotatable members provided with friction surfaces between which said strand of hair is drawn by the winding element, resilient members mounted on said frame and adapted when in one position to permit the separation of said members, and when in another position to press said members towards each other and to resiliently hold the same in contacting engagement with each other, the friction surfaces of said members being incapable of movement relative to each other when the same are in locked contacting engagement with each other.

11. A hair waving device, including a pair of frame members pivotally secured to each other,

each of said frame members comprising a pair of side arms to the free ends of which is secured a connecting rod, upon which is provided a friction surface incapable of movement relative to said connecting rod, means for moving said frames to bring the friction surfaces thereof into contacting engagement with each other, and resilient means for locking said friction surfaces in such contacting engagement.

10 12. A hair waving device, including a pair of frame members pivotally secured to each other, each of said frame members comprising a pair of

side arms to the free ends of which is secured a connecting rod, upon which is provided a friction surface incapable of movement relative to said connecting rod, means for moving said frames to bring the friction surfaces thereof into contacting engagement with each other, and resilient means for locking said friction surfaces in such contacting engagement, said side arms of said frame members having means provided therein for receiving and revolvably holding the 10 winding element therein.

RENATO LUDOVICI.
